ATTORNEY

UNITED STATES PATENT OFFICE.

WILLIAM C. K. BUCHANAN, OF CHICAGO, ILLINOIS.

INHALER.

Application filed August 18, 1919. Serial No. 318,084.

To all whom it may concern:

Be it known that I, WILLIAM C. K. BUCHANAN, a citizen of the United States, residing at Chicago, in the county of Cook and State of Illinois, have invented a certain new and useful Improvement in Inhalers, of which the following is a specification.

My invention relates to an improved device for containing more or less volatile liquid for perfuming and disinfecting purposes. My device is constructed to contain said liquid and permit the ready passage through the device of air without the possibility of the liquid running out of the containing device. The device may be used for a variety of purposes, such for example as a perfuming means either in the open air or in receptacles containing clothing, and as an inhaler.

My invention also includes means for holding the device in place when used as an inhaler so that it is unnecessary to use the hands for the purpose. My improved device consists essentially of a receptacle of material not attacked by the liquid contained therein having reentrant tubes of the same material extending from the outer surface of the receptacle into the same to retain the liquid in place and provide passages for the flow of air into and from the receptacle. My invention also provides devices for closing the said tubes partially or wholly as desired to prevent loss of the volatile liquid when the device is not in use.

My invention will best be understood by reference to the accompanying drawings showing preferred embodiments thereof in which—

Fig. 1 shows an inhaler constructed in accordance with my invention in elevation and a device secured thereto by which the inhaler may be held in operative position by the teeth of the user.

Fig. 2 is a longitudinal sectional view taken along the line 2—2 of the inhaler shown in Fig. 1 with the holding device removed.

Fig. 3 is a sectional view on an enlarged scale of the parts shown in Fig. 2 taken along the line 3—3,

Fig. 4 shows in a view similar to Fig. 3 a slightly modified construction as to the shape of the cross section of the reentrant tube,

Fig. 5 shows in enlarged sectional view 55 one of the valves employed in the construction shown in Fig. 2, and

Fig. 6 shows in a view similar to Fig. 2 one end of an inhaler without the valve mechanism employed in Fig. 2 and in this construction a retaining means is provided in the reentrant tube for restricting the flow of air therethrough and preventing the accidental spilling of the liquid from the inhaler if it is shaken, 60 65

Similar numerals refer to similar parts throughout the several views.

As shown in Fig. 2 the container for the liquid is in the form of a tube 10 having rounded ends, said ends being inturned to 70 form reentrant central tubes 11 and 12 of smaller diameter than the tube 10. The tubes 11 and 12 are provided with inwardly projecting annular flanges 13 and 14 and at their inner ends said tubes are of reduced 75 diameter as indicated at 15 and 16. The outer portions of the tubes 11 and 12 are provided with oppositely disposed inwardly projecting longitudinal flanges 17 and 18. A rod 19 of smaller diameter than the inner diameter of the ends 15 and 16 of the tubes 11 and 12 extends through nearly the whole length of the inhaler and at one end has rigidly secured thereto a cap 20 by means of which the rod may be turned. 80 85

Adjacent the flanges 13 and 14, nuts 21 and 22 are disposed upon said rod in engagement with threads thereon, the threads in the nut 21 being left-handed and the threads in the nut 22 being right-handed. As more 90 clearly shown for the nut 22 in Fig. 3 each of said nuts is provided with opposite notches to clear the inwardly projecting longitudinal flanges above referred to. Each of the said nuts is preferably formed as indicated for the nut 22 in Fig. 5 and consists of a disc 22^a of metal having the threads referred to formed in it and provided at its outer edge with a flange for retaining a disc 22^b of relatively soft material such as cork to constitute the portion of the valve engaging the flange 14. 95

As a result of the construction described when the cap 20 is moved in one direction both of the nuts 21 and 22 are moved away 100 105 from the flanges 13 and 14 and air may be drawn through the tubes 11 and 12 freely. When the cap 20 is turned in the opposite

direction the nuts 21 and 22 are moved towards the flanges 13 and 14 until the valve discs are firmly seated against said flanges to prevent the flow of air through the container. The tube 10 and the tubes 11 and 12 are preferably made of transparent material such as glass or transparent material such as celluloid or other composition not attacked by the liquid used in the inhaler so that the quantity of liquid in the inhaler may readily be seen at any time. To charge the inhaler with liquid containing the desired disinfecting or healing substances the inhaler is held in inclined position with the nuts 21 and 22 moved from engagement with the flanges 13 and 14 and the liquid is inserted in the outer end of the upper reentrant tube through which it runs, dropping into the outer tube 10. This is continued until the liquid in the outer tube is somewhat below the upper end of the lower reentrant tube and with this quantity of liquid in the tube it will not be discharged therefrom for any position of the inhaler since the only possible outlet is always above the level of the liquid in the inhaler. For some purposes it is not necessary to have the valve mechanism above described in which case I find it desirable to place fibrous material 23 in the reentrant tubes as shown for the tube 12^a in Fig. 6 in which case the flange 14^a serves to hold the fibrous material such as absorbent cotton in place. In this way I prevent the flow of air through the tube being so violent as to suck out the liquid with it and I also provide that the liquid cannot be spilled from the inhaler by shaking the same.

To facilitate holding the inhaler in proper position for use I find it convenient to employ a ring of wire spring 24 as shown in Fig. 1 which must be stretched somewhat to slip onto the inhaler and to one side of said ring I rigidly secure a curved member 25 which is preferably provided with a somewhat enlarged projecting end 26 to be engaged by the teeth of the user. In this way the supporting device may be adjusted on the inhaler so that the teeth of the user will hold the inhaler conveniently and securely in operative position for as long a time as it is desired to use the inhaler, leaving the hands of the user entirely free during the interval of use.

In the slightly modified construction shown in Fig. 4 the reentrant tube 12^b is of oval cross section and the nut 22^b is of similar form, as a result of which the form of the tube 12^b itself prevents turning of the nut in the tube and thus the longitudinal flanges above referred to are not required. Where it is not desirable or necessary to use the valve mechanism shown in Fig. 2, the outer ends of the reentrant tubes may be closed when not in use by means of small

plugs or corks as indicated at 27 in Fig. 6 for the tube 12^a.

An important result secured by the use of my improved holding means for the inhaler, is that the tendency to use the inhaler too hurriedly by forced breathing and inhalation is eliminated and the user gets better results by natural breathing continued for a longer time interval. While the chemicals or drugs employed in the inhaler may be well suited for inhalation by natural breathing, it frequently happens that in forcing the inhalation by unusually deep or vigorous breathing, the volatile chemicals or drugs are drawn into the system in such large doses as to seriously irritate the mucous membranes, particularly in sensitive cases, and in many cases causing derangement of the stomach and digestive processes; all of this is obviated by the use of my holding devices, since with them there is no inconvenience in holding the inhaler in place and the inhalation can proceed by natural breathing for any desired time interval without preventing other activity of the user.

While I have shown my invention in the particular embodiments above described I do not however limit myself to these exact constructions in carrying out my invention as I may employ equivalents thereof known to the art at the time of the filing of this application without departing from the scope of the appended claims.

What I claim is:

1. In a device of the class described, the combination of a receptacle for containing the liquid to be vaporized, reentrant tubes projecting towards each other from opposite ends of said receptacle forming an open passageway for air through said receptacle, said tubes retaining said liquid in the receptacle without spilling for any position of said receptacle, and devices for closing said tubes, said devices comprising a rod extending through said tubes and having right hand and left hand threads on its end portions, valve disks threaded to fit said threaded end portions, and transverse flanges extending inwardly from said tubes to form seats for engaging said valve disks.

2. In a device of the class described, the combination of a receptacle for containing the liquid to be vaporized, reentrant tubes projecting towards each other from opposite ends of said receptacle forming an open passageway for air through said receptacle, said tubes retaining said liquid in the receptacle without spilling for any position of said receptacle, and devices for closing said tubes, said devices comprising a rod extending through said tubes and having right hand and left hand threads on its end portions, valve disks threaded to fit said threaded end portions, and transverse flanges ex-

tending inwardly from said tubes to form seats for engaging said valve disks, said tubes being of a cross section preventing turning of said valve disks.

5 3. In a device of the class described, the combination of a receptacle for containing the liquid to be vaporized, reentrant tubes projecting towards each other from opposite ends of said receptacle forming an open passageway for air through said receptacle, said tubes retaining said liquid in the receptacle without spilling for any position of said receptacle, and devices for closing said tubes, said devices comprising a rod extending through said tubes and having right hand and left hand threads on its end portions, valve disks threaded to fit said threaded end portions, transverse flanges extending inwardly from said tubes to form seats for engaging said valve disks, and means for holding said receptacle in inhaling position comprising a ring surrounding said receptacle, and a supporting member secured to said ring. 70

5. In a device of the class described the combination of a receptacle for containing the liquid to be vaporized, reentrant tubes projecting towards each other from opposite ends of said receptacle forming an open passageway for air through said receptacle, said tubes retaining said liquid in the receptacle without spilling for any position of said receptacle, and devices for closing said tubes, said devices comprising a rod extending through said tubes and having right hand and left hand threads on its end portions, valve disks threaded to fit said threaded end portions, transverse flanges extending inwardly from said tubes to form seats for engaging said valve disks, and an enlarged head on said rod to facilitate turning the same, said head forming a cap to close the outer end of one of said tubes when said valve disks are on their seats. 110

7. In a device of the class described, the combination of a receptacle for containing the liquid to be vaporized, reentrant tubes projecting towards each other from opposite ends of said receptacle forming an open passageway for air through said receptacle, said tubes retaining said liquid in the receptacle without spilling for any position of said receptacle, and means for holding said receptacle in inhaling position comprising a spring ring surrounding said receptacle, and a supporting member secured to and extending from said ring to be engaged by the teeth of the user. 95

8. In a device of the class described, the combination of a receptacle for containing the liquid to be vaporized, reentrant tubes projecting towards each other from opposite ends of said receptacle forming an open passageway for air through said receptacle, said tubes retaining said liquid in the receptacle without spilling for any position of said receptacle, said tubes having inwardly projecting flanges, fibrous material held in said tubes by said flanges, means for holding said receptacle in inhaling position comprising a spring ring surrounding said receptacle, and a supporting member secured to and extending from said ring to be engaged by the teeth of the user. 100

to and extending from said ring to be engaged by the teeth of the user.

10. In a device of the class described, the combination of a tubular receptacle for containing liquid, said receptacle having enclosed ends, and tubes of smaller diameter than the bore of said receptacle extending towards each other from said ends and having their axes coaxial with the axis of said

receptacle, said tubes having indentations 10 therein for retaining fibrous material in said tubes, and having also ends of restricted diameter opening in line with each other.

In witness whereof, I hereunto subscribe my name this 15th day of August, A. D. 15 1919.

WILLIAM C. K. BUCHANAN.
